[57] CLAIM

The ornamental design for a flowmeter, as shown and
described.

DESCRIPTION

FIG. 1 is a top plan view of a flowmeter showing my
new design;

FIG. 2 is a bottom plan view thereof;

FIG. 3 is a side elevational view thereof;

FIG. 4 is a rear elevational view thereof;

FIG. 5 is a front elevational view thereof;

FIG. 6 is a top plan view of a flowmeter showing another
embodiment of my new design wherein the
mounting brackets shown in the embodiment of FIG. 1
are removed;

FIG. 7 is a bottom plan view thereof;

FIG. 8 is a side elevational view thereof;

FIG. 9 is a rear elevational view thereof; and

FIG. 10 is a front elevational view thereof.

In each embodiment of the flowmeter, the side elevational
view of the flowmeter not shown is substantially
the same as the side elevational view shown.
